UNITED STATES PATENT OFFICE.

WILLIAM A. SCHRAUBSTADTER, OF ST. LOUIS, MISSOURI, ASSIGNOR TO INLAND TYPE FOUNDRY, OF ST. LOUIS, MISSOURI, A CORPORATION OF MISSOURI.

DESIGN FOR A FONT OF TYPE.

No. 39,125.

Specification for Design.

Patented Feb. 11, 1908.

Application filed January 19, 1905. Serial No. 241,897. Term of patent 7 years.

To all whom it may concern:

Be it known that I, WILLIAM A. SCHRAUBSTADTER, a citizen of the United States, and a resident of the city of St. Louis and State of Missouri, have invented a new, original, and ornamental Design for a Font of Type, of which the following is a specification.

My design consists of an alphabet of capital letters, with figures, points, short-and, dollar mark, and sterling pound mark, of the style called "condensed comstock", each character being perpendicular and the top and bottom thereof, respectively, being in the same horizontal plane with the exception of the letter Q, each line of each character being of the same width and surrounded by a hair line,

What I claim is:

The ornamental design for a font of type as herein shown and described.

WM. A. SCHRAUBSTADTER.
